(57) **CLAIM**

The ornamental design for a hockey stick, as shown and described.

DESCRIPTION

FIG. 1 is a front left perspective view of a right-handed hockey stick showing my new design;

FIG. 2 is a left side view thereof;

FIG. 3 is a right side view thereof;

FIG. 4 is a front view thereof;

FIG. 5 is a rear view thereof;

FIG. 6 is a bottom view thereof;

FIG. 7 is a bottom view thereof;

FIG. 8 is a front right perspective view of a left-handed hockey stick;

FIG. 9 is a right view of FIG. 10;

FIG. 10 is a left view of FIG. 10;

FIG. 11 is a front view of FIG. 10;

FIG. 12 is a rear view of FIG. 10;

FIG. 13 is a bottom view of FIG. 10; and,

FIG. 14 is a top view of FIG. 10.

The uneven-length broken lines immediately adjacent to the shaded area represent unclaimed boundaries of the design.

The even-length broken lines showing the remainder of the hockey stick represent unclaimed subject matter and form no part of the claimed design.

1 Claim, 14 Drawing Sheets
